FOREIGN PATENT DOCUMENTS

WO 2014055724 A1 4/2014

Primary Examiner — Mark A Goodwin*(74) Attorney, Agent, or Firm* — Michael Best & Friedrich LLP(57) **CLAIM**

We claim the ornamental design for a cutter, as shown and described.

DESCRIPTION

FIG. 1 is a rear perspective view of a cutter according to the present invention.

FIG. 2 is a rear view of the cutter of FIG. 1.

FIG. 3 is a front view of the cutter of FIG. 1.

FIG. 4 is a left side view of the cutter of FIG. 1.

FIG. 5 is a right side view of the cutter of FIG. 1.

FIG. 6 is a top view of the cutter of FIG. 1; and,

FIG. 7 is a bottom view of the cutter of FIG. 1.

The portions of the cutter shown in broken lines form no part of the claimed design, including the dash-dot lines used as boundary lines.

1 Claim, 4 Drawing Sheets(56)
